SPEAKER ENCLOSURE

Aston L. Moore, 220 Hammond Place,
South Bend, Ind. 46601

Filed Sept. 27, 1967, Ser. No. 8,75:

Term of patent 14 years

(Cl. D26—14)

FIGURE 1 is a top perspective view of a speaker enclosure, showing my new design, the partially disclosed bottom perspective view being substantially the same in appearance;

FIGURE 2 is a fragmentary side elevational view enlarged with respect to FIGURE 1, the opposite side being substantially a mirror image thereof, the portion broken away to indicate indeterminate height being identical to portions adjacent the break;

FIGURE 3 is a top plan view, enlarged with respect to FIGURE 2; and

FIGURE 4 is a bottom plan view, to the same scale as FIGURE 3,

The dominant features of the design are as shown in solid lines.

I claim:

The ornamental design for a speaker enclosure, as shown and described.
